Primary Examiner — Samantha Wood(74) *Attorney, Agent, or Firm* — Heisler & Associates(57) **CLAIM**

The ornamental design for a hydrofoil bike, as shown and described.

DESCRIPTION

FIG. 1 is a perspective view of a hydrofoil bike showing our new design.

FIG. 2 is a back view of that which is shown in FIG. 1.

FIG. 3 is a right view of that which is shown in FIG. 1.

FIG. 4 is a left view of that which is shown in FIG. 1.

FIG. 5 is a top view of that which is shown in FIG. 1.

FIG. 6 is a bottom view of that which is shown in FIG. 1.

FIG. 7 is a side perspective view of that which is shown in FIG. 1; and,

FIG. 8 is a top perspective view of that which is shown in FIG. 1.

The broken lines are included for the purpose of illustrating unclaimed subject matter and form no part of the claimed design.

1 Claim, 8 Drawing Sheets(56)
